UNITED STATES PATENT OFFICE.

DAVID F. CRAWFORD, OF PITTSBURGH, PENNSYLVANIA, ASSIGNOR TO LOCOMOTIVE STOKER COMPANY, OF PITTSBURGH, PENNSYLVANIA, A CORPORATION OF PENNSYLVANIA.

LOCOMOTIVE DRAFT APPLIANCE.

1,356,808.

Specification of Letters Patent. Patented Oct. 26, 1920.

Application filed March 3, 1919. Serial No. 280,295.

To all whom it may concern:

Be it known that I, DAVID F. CRAWFORD, a citizen of the United States, residing at Pittsburgh, in the county of Allegheny and 5 State of Pennsylvania, have invented certain new and useful Improvements in Locomotive Draft Appliances, of which the following is a specification.

This invention relates to draft appliances 10 and particularly to that class of apparatus in which draft is created by a blower fan operated by a turbine or other form of engine, utilizing exhaust steam.

Heretofore, in this class of apparatus all 15 of the exhaust steam is passed through the turbine, as a result of which it is impossible to maintain proper draft conditions, particularly when the locomotive is working hard, in which case the turbine would rotate at too 20 high a rate of speed, thus greatly increasing the draft and causing "popping" or waste of steam in some instances, and in others pulling the fire out of the box.

It is one of the primary objects of my invention to overcome the foregoing difficulties 25 and to provide an improved apparatus whereby the draft may be simply regulated to suit all operating conditions. My invention also contemplates an improved arrangement 30 of the draft appliance whereby back pressure is substantially eliminated.

I accomplish the foregoing together with such other objects as may hereinafter appear, by means of a construction which I 35 have illustrated in preferred form in the accompanying drawings wherein—

Figure 1 is a longitudinal section through the smoke box of a locomotive showing my improvements applied thereto; and Fig. 2 is 40 a transverse section taken on the line II—II of Fig. 1.

In the drawings I have shown my improvements in connection with a blower apparatus of the steam turbine type. The smoke box is indicated as a whole at A and the draft appliance comprises a blower fan 45 carried on the shaft 8 of a steam turbine 9, which may be located inside or outside of the smoke box. The blower fan operates in 50 the usual manner and sets up a draft which draws the products of combustion from the fire box through the flues into the smoke box, the cinders being caught by a series of baffles, indicated as a whole at B. The 55 tail construction of the internal mechanism

of the turbine 9 forms no part of the present invention.

Exhaust steam from the cylinders is led into the passageway 11 of the casting 11. The passageway 11 opens into a passageway 60 12 which communicates with the annular steam chamber 13 of the turbine, and into a passageway 14 which communicates with a bypass 15, arranged exteriorly of the turbine. The two passageways 12 and 14 are 65 preferably controlled by a single rotary valve element 16. At the top, the bypass 15 is provided with a discharge outlet 17, and the exhaust steam from the turbine discharges through an outlet 18. 70

The operation of the device will be clearly seen from the following: The valve 16 may be shifted to a position completely closing off passageway 12 and uncovering the passageway 14. In this position all of the exhaust steam is by-passed around the turbine and discharges through the stack 19. The turbine and fan may be thus rendered inoperative when no special draft is necessary. Or the valve may be shifted to entirely uncover passageway 12 and close passageway 14, in which position the turbine and fan will produce maximum draft because all of the exhaust steam will pass through the turbine. Or the valve may be shifted to any 80 intermediate position in which any desired volume of steam may be passed through the turbine and the remainder by-passed, as a result of which the speed of the fan may be controlled to produce any required draft 85 conditions. It will be seen therefore, that by proper manipulation of the valve, the draft may be varied to suit all operating conditions and efficient and economical operation of the locomotive obtained. 90 95

It is also to be observed that I am enabled to largely or substantially eliminate back pressure. In this connection I prefer to construct the passages 12 and 14 and the chambers 13 and 15 with no restrictions in area 100 relative to the area of the exhaust passages from the cylinders, so that substantially the only back pressure created is the slight pressure incident to turning the turbine and fan, which is negligible as a matter of ordinary 105 practice.

I claim:

1. A locomotive draft appliance comprising in combination a draft producing means, an engine for driving the same operated by 110

exhaust steam from the cylinders, means for conveying the steam thereto, and means by-passing the steam.

2. A variable locomotive draft appliance comprising in combination a draft producing means, an engine for driving the same operated by exhaust steam from the cylinders, means for conveying the steam thereto, and means for varying the draft comprising means for by-passing steam.

3. A locomotive draft appliance comprising in combination a draft producing means, an engine for operating the same utilizing exhaust steam from the cylinders, means for conveying the steam thereto, means for bypassing the steam, and a single element governing said last two means.

4. A locomotive draft appliance comprising in combination a draft producing means,

an engine for operating the same utilizing exhaust steam from the cylinders, the appliance being provided with two passages, one for conducting the steam to the engine and the other for by-passing the steam, and a valve controlling both passages.

5. A locomotive draft appliance comprising in combination a draft producing means, and an engine for operating the same utilizing exhaust steam, the appliance being provided with a conduit for conveying steam to the engine and with by-passing means substantially unrestricted in area relative to the area of the exhaust passages from the cylinders.

In testimony whereof, I have hereunto signed my name.

DAVID F. CRAWFORD.
